Primary Examiner — Brett Miller*Assistant Examiner* — Rani J Abdallah(74) *Attorney, Agent, or Firm* — Duane Morris LLP(57) **CLAIM**

The ornamental design for a shave preparation container, as shown and described.

DESCRIPTION

FIG. 1 is a front perspective view of a shave preparation container;

FIG. 2 is a bottom perspective view thereof, showing a mirrored surface bottom;

FIG. 3 is a bottom plan view thereof;

FIG. 4 is a partial side elevation cross-sectional view, taken through line 4-4 in FIG. 3, showing the mirrored surface from the side; and,

FIG. 5 is a front elevation view thereof.

The portions shown in dash-dot broken line depict boundaries of the claim and form no part of the claimed design.
